UNITED STATES PATENT OFFICE.

LOUIS JURAK, OF CHICAGO, ILLINOIS.

GAME.

1,249,413.

Specification of Letters Patent. Patented Dec. 11, 1917.

Application filed December 14, 1915. Serial No. 66,771.

To all whom it may concern:

Be it known that I, Louis JURAK, a subject of the Emperor of Austria, residing at Chicago, in the county of Cook and State of Illinois, have invented certain new and useful Improvements in Games; and I do hereby declare the following to be a full, clear, and exact description of the invention, such as will enable others skilled in the art to which it appertains to make and use the same.

This invention relates to games and more particularly to a game wherein a board is provided with a plurality of pits for receiving balls, which are deflected by a curved upstanding ball deflecting wall attached to one end of the board.

The primary object of the invention is to provide in a game board structure as specified, a game board which is positioned at an incline and has a pair of channels positioned at each side of the same and terminating at the uppermost end of the board so that the ball projected upwardly through the channels will be released therefrom at the upper end of the board for engagement against an upstanding arcuate ball deflecting wall which will deflect the ball downwardly over the surface of the board and to provide a plurality of pits within the upper surface of the board in which the balls are to be deposited, and further to provide a plurality of hazards which include pins for deflecting the travel of the balls and increasing difficulty in placing the balls in the various pits, making it a game of chance, rather than skill.

A further object of this invention is to provide a receiving trough or trench at the lower end of the board which has its outer wall constructed of a pair of hingedly supported sections which meet intermediate the ends of the trough and are held in closed position by any suitable type of catch mechanism, into which trough the balls travel or fall after a passage over the upper surface of the boards, and to provide a second trough which is positioned beneath the first named trough for receiving the balls therefrom.

With the foregoing and other objects in view this invention consists in such novel features of construction, combination and arrangement of parts as will be hereinafter more fully described, illustrated in the accompanying drawings, and claimed.

In describing the invention in detail reference will be had to the accompanying drawings wherein like characters designate like and corresponding parts throughout the several views, and in which:—

Figure 1 is a plan view of the improved game board.

Fig. 2 is a longitudinal section through the game board. 65

Fig. 3 is an end view of the game board.

Fig. 4 is a fragmentary section on the line 4—4 of Fig. 1, and

Fig. 5 is a detail view of a cue used in connection with the game. 70

Referring more particularly to the drawings, 1 designates the game board, which is supported at an incline, by a suitable supporting structure 2. The board 1 has its upper end curved, as is clearly shown at 3 in Fig. 1 of the drawings, and an upstanding ball deflecting wall 4 is attached to the upper surface of the upper end of the board 1 and extends about the curved end of the same, having its end meeting the upper end of the upstanding outer wall 5 of the side channels 6 and 7. The ball deflecting wall 4 has its inner surface 8 cut angularly with respect to the perpendicular, for more efficiently guiding the ball and it is of greater height than the side walls 5, for preventing the balls indicated at 9 from jumping over the deflecting wall 4. 80

The upper surface of the board 1 is provided with a plurality of pits 10 which have various indicating characters 11 positioned above the same for indicating the number of points the player of the game receives when one of the balls are deposited in any one of the pits. Hazards are provided, for rendering more difficult the depositing of the balls 9 in any one of the pits 10, which hazards comprise pins 12 which extend perpendicularly from the upper surface of the board 1 and are arranged in any suitable manner for making it a game of chance rather than a game of skill. 95

The channels 6 and 7 are formed by the outer upstanding side walls 5 and the inner upstanding side walls 14 and 15 respectively. 105 The inner side wall 15 of the channel 7 is slightly longer than the side wall 14 in order to provide a stronger lead to a ball deflected or forced upwardly through the channel 7. The inner upstanding side walls 14 and 15 of the channels 6 and 7 terminate a short distance inwardly from the lower edge of 110

the board to provide an inserting mouth for placing the balls within the channels. A board 20 is attached to the lower edge of the game board and extends outwardly and downwardly at an incline, as is clearly shown in Fig. 2 of the drawings. The upper edge of the board 20 is flush with the upper surface of the game board 1, and it, in combination with the boards 21 and 22 form 5 a trough or trench 23 in which the balls which fail to fall in any one of the pits 10 roll, after a complete travel over the full length of the upper surface of the board 1. The boards or strips 21 or 22 are hingedly 10 connected as is shown at 24 to the end 27 of the trough. The meeting ends of the bars 21 and 22, which meet substantially at the center of the trough, are connected by any suitable type of flexible or elastic ma- 15 terial as indicated at 28, so that they may be drawn outwardly into the position indicated in dotted lines in Fig. 1 of the drawings for permitting the balls to fall therefrom into the trough 29 which is positioned 20 directly beneath the trough 23 and is attached to the supporting structure 2 of the board 1.

In Fig. 5 of the drawings, a cue 30 is shown which has its tip end 31 provided 30 with a concave recess 32 for engaging the balls 9 and forcing them upwardly through the channels 6 or 7 while playing the game.

In playing the game, a ball 9 is placed 35 in either of the channels 6 or 7 at the lower end of the same and it is propelled upwardly by a player, with the cue 30. The ball reaching the upper delivery end of the channel will engage the deflecting wall 4 and be deflected downwardly over the upper 40 surface of the board 1. The travel of the ball will be deflected by the pins 12, and in case the ball drops in any one of the pits 10, the player shooting the ball will be credited with the number of points which the pit 45 represents in accordance with the indications 11. The balls which do not fall in any one of the pits, travel throughout the entire length of the board, and into the chan-

nel 23. When one person has shot the desired number of balls, the bars 21 and 22 are 50 moved outwardly on their hinged connection which permit the balls to drop downwardly into the trough 29. The balls remaining in the channel or trough 23 until the player has finished his play will enable the score 55 keeper to readily count the number of balls shot by each player.

From the foregoing description taken in connection with the accompanying drawings the advantages of construction and of the 60 method of operation of the improved game will be readily apparent to those skilled in the art to which this invention appertains and, while in the foregoing description, the principle of the operation of this invention 65 has been described together with various features of construction, it is to be understood that certain minor features of construction combination and arrangement of parts may be altered to suit practical conditions provided such alterations are comprehended within the scope of what is claimed.

What is claimed is:—

A game comprising a supporting structure, an inclined game board carried by said 75 structure, an outwardly and downwardly inclined member secured to the lower edge of the game board and extending the entire width thereof, strips hinged to each side edge of the game board and extending in 80 the direction of each other, an elastic member connecting the free ends of strips and holding said strips in engagement with the inclined member to form a trough to receive balls, and a second trough carried by the 85 supporting structure and adapted to receive the balls upon moving the strips against the tension of the elastic member from engagement with the inclined member.

In testimony whereof I affix my signature 90 in presence of two witnesses.

LOUIS JURAK.
